United States Patent

Des. 237,288
Patented Oct. 21, 1975

237,288

TOY MOBILE

Ralph W. Crawford, East Aurora, N.Y., assignor to
The Quaker Oats Company, Chicago, Ill.

Filed Dec. 5, 1973, Ser. No. 421,776

Term of patent 14 years

Int. Cl. D21—01

U.S. Cl. D34—15 F

FIG. 1

FIG. 3

FIG. 2

FIG. 4

FIG. 1 is a front perspective view of a toy mobile showing my new design;

FIG. 2 is a top plan view thereof shown on an enlarged scale;

FIG. 3 is a rear elevation thereof with the vertical portion of the arm broken away for purposes of clarity; and

FIG. 4 is a bottom plan view with the horizontal portion of the arm broken away for purposes of clarity.

I claim:

The ornamental design for a toy mobile, substantially as shown and described.
